UNITED STATES PATENT OFFICE.

MYRON W. PARRISH, OF DETROIT, AND MARCUS F. PARRISH, OF NILES, ASSIGNEES OF ONE-THIRD TO HORACE B. PECK, OF ALLEGAN, MICHIGAN.

ELECTRIC SIGNAL APPARATUS.

SPECIFICATION forming part of Letters Patent No. 322,474, dated July 21, 1885.

Application filed March 28, 1885. (No mod.-i.)

To all whom it may concern:

Be it known that we, MYRON W. PARRISH and MARCUS F. PARRISH, citizens of the United States, the former residing at Detroit, county 5 of Wayne, the latter residing at Niles, county of Berrien, State of Michigan, have jointly invented a new and useful Electric Signal Apparatus, of which the following is a specification.

10 This invention consists in the novel construction and association of parts constituting a new electric signal apparatus especially designed for use on railway-trains, but equally applicable for use in fire and burglar alarms, 15 and for other purposes. The objects attained are set forth in the following description and claims.

A general description consists in two electric circuits, one of which is of a higher resistance than the other, an electrical generator, or a battery, if preferred, connecting the two circuits or being in said circuits, and a signal-bell (or other suitable alarm or signal device capable of being operated by an electric current) in the circuit of the higher resistance, and circuit-breakers in the circuit of the lower resistance—one or more—the whole so constructed and arranged that a break in the circuit of the lower resistance causes the 20 bell to be rung by the circuit of the higher resistance, and consequently not to ring when the circuit of the lower resistance remains unbroken—that is, breaking the latter circuit rings the bell, and "making" the said 25 latter circuit stops the bell from ringing.

In the drawings, forming a part of this specification, Figure 1 shows a side elevation of a railway-train with the apparatus adapted and connected for use. Fig. 2 is an enlarged detail of Fig. 1 in perspective, showing the arrangement of the circuits, and Fig. 3 is an enlarged detail of parts in Fig. 1, referred to by like letters; and Fig. 4 is a diagrammatical view of the two circuits shown 30 independent of the generator-case and train of cars.

Referring to Fig. 2, a case is shown, in the part D of which is a generator, and on the top of part C is a bell, *i i*, made in the usual 35 manner. The generator is not here shown,

for the reason that its construction and connection and relation with an electric bell are well understood. The generator may be operated by any suitable means, no operating means being here shown. In lieu of a generator, a battery may be employed. The circuit of higher resistance connects the generator and bell, the only portion of said circuit which appears visible being the wires *c* 40 *c'*, connecting the posts *x x* (which are in the circuit and extend through the case) with the posts *e e* of said circuit. The remaining part of the circuit within the case, in which part of the circuit are the bell and the generator, is shown diagrammatically in Fig. 4. The 45 generator 1 is thus seen in both circuits and the alarm-bell *i* in the circuit of the higher resistance. The common magnets 2 2 in such signal-circuits of course contain in their metallic coils a larger amount of wire than the 50 lower-resistance circuit *a c*. Thus when the latter-named circuit is "broken" or virtually destroyed the higher-resistance circuit rings the bell at the place desired for it to be sounded, and the breaking of the lower-resistance 55 circuit, it will be observed, is effected by the operator at the point from whence the signal is sent. Thus the action of the operator to send the signal is the action which destroys for the time being the lower-resistance circuit. 60 The electric current of the circuit just described will ring the bell continuously while the generator is running until the circuit is broken or is robbed of its electric current.

In order that the bell may be under the control of the operator, a distance away from the bell-circuit just described, we connect another circuit, *a c*, with the generator, Fig. 2, of a lower resistance than the bell-circuit, and when thus connected the bell-circuit becomes a circuit of high resistance as compared to the circuit of a lower resistance. As now described and shown in Fig. 2, the bell will not ring, although the generator be running, for the reason that the circuit of low resistance has 75 robbed the circuit of higher resistance of its power to ring the bell. By breaking the circuit *a c* it virtually no longer constitutes a circuit, and the whole supply of electricity from the generator plays on the bell-circuit 80

and the bell rings. The bell will ring continuously while the circuit of the lower resistance is broken, and by alternately breaking and making said latter circuit the bell will 5 give an interrupted succession of sounds.

At D' a circuit-breaker is shown in the circuit *a c*, consisting of a case, *v*, within which is fixed a flexible hair-pin-shaped bar, *t*, one end of which is left free to detachably contact 10 with the metal of the case, and a push-button, *r*, for operating the same. By pushing on this button the free end of the flexible bar *t* is disconnected or carried away from its metal contact, which action breaks the circuit *a c*, causing 15 the bell to be rung by the other circuit, as before described.

Any suitable circuit-breaker may be employed at the location in the circuit desired or at different locations, as shown in Fig. 1, 20 when connected with a car.

Similar devices, called "push-buttons," have been heretofore used for closing or making a bell-circuit, and thereby ring the bell. When using the signal connected with a train of cars, 25 the design is to place the generator, bell, and bell-circuit in the engine-cab, Fig. 1, and extend the circuit of lower resistance through the cars. The parallel wires of said circuit *a c* are detachably coupled together between 30 the cars, as at *s*, so as to be uncoupled by pulling apart, Fig. 3. When thus coupled, should one car become detached from another, or the train break apart, the strain on the couplings *s* would pull them apart, thus breaking the 35 circuit of a lower resistance, which would cause the bell in the cab to ring continuously. Thus the engineer, by the nature of the signal, would know that an accident had happened 40 to the low-resistance circuit, and would stop the engine at once, instead of running miles, as is frequently the case, before discovering that a part of his train had become detached.

Any well-known style of coupling or otherwise, at *s*, may be employed to detachably 45 couple the sections of the circuit of lower resistance. By "sections" is meant the wires of the circuit in each car, Fig. 1. Of course the terminal end of the wires *a c* through the end of the rear car are coupled together 50 when in use, thus making the circuit.

From the foregoing it will be seen that our invention may have many uses not requiring the circuit-breakers D, which in a car are designed for the conductor's use, for the reason 55 that any disconnection of one of the wires *a c*, or a detaching of one of the sections, as above defined, from another, will cause the alarm to be sounded. As means for propelling the generator in the engine-cab are al-

ready known, and as we are making other inventions having reference to the generator and means for propelling the same, no details of said means are here described.

We do not wish to be limited to the exact mechanical details of our invention herein described, the purpose of the illustrations being designed to show its operativeness and practicability. In adapting the two defined circuits, the generator or battery and bell or signal, to the many uses to which these associated parts may be applied, it will appear obvious that any suitable mechanical details may be followed.

The novelty and utility of our invention will appear obvious from the foregoing, it is 75 deemed, when contrasting it with the old apparatus, in which the bell-circuit is extended through the train of cars, and which requires to be made instead of broken to ring the bell, and in which only one circuit is employed.

Having thus described our invention, what we claim as new, is—

1. An electric signal apparatus, consisting of two circuits, one of a higher resistance than the other, the circuit of higher resistance being located at the place where the signal is to be sounded, a generator or battery in the circuits, a signal or alarm in the higher-resistance circuit, and a signaling circuit-breaker in the lower-resistance circuit at a point from whence the signal is to be sent, substantially as set forth.

2. The combination, with a train of cars, of a high-resistance circuit located in the engine, a lower-resistance circuit running through the train, a generator or battery in the circuits, an alarm or signal in the higher-resistance circuit, and one or more signaling circuit-breakers in the lower-resistance circuit in the cars, substantially as set forth.

3. The combination, with a train of cars, of a high-resistance circuit located in the engine, a lower-resistance circuit running through the train, a generator or battery in the circuits, and a signal or alarm in the high-resistance circuit, whereby an alarm would be sounded in the engine by an accidental breaking or separation of the lower-resistance circuit, substantially as set forth.

In testimony of the foregoing we have hereunto subscribed our names in presence of two witnesses.
